US0D1010106S

(12) **United States Design Patent** (10) **Patent No.:** **US D1,010,106 S**
(45) **Date of Patent:** **** Jan. 2, 2024**

(54) **DRUG INFUSION DEVICE**

(71) Applicant: **MEDTRUM TECHNOLOGIES INC.**,
Shanghai (CN)

(72) Inventor: **Cuijun Yang**, Shanghai (CN)

(73) Assignee: **MEDTRUM TECHNOLOGIES INC.**,
Shanghai (CN)

(**) Term: **15 Years**

(21) Appl. No.: **29/828,214**

(22) Filed: **Feb. 24, 2022**

(30) **Foreign Application Priority Data**

Sep. 27, 2021 (CN) 202130642918.7

(51) **LOC (14) Cl.** **24-02**

(52) **U.S. Cl.**

USPC **D24/111**; D24/112

(58) **Field of Classification Search**

USPC D24/113, 130, 111, 112; D13/162, 184;
D14/203.5, 203.8, 341, 344, 192, 191

CPC A61M 5/14244; A61M 5/14248; A61M
2005/14252

(57) **CLAIM**

The ornamental design for a drug infusion device, as shown and described.

DESCRIPTION

FIG. 1 is a perspective view of a drug infusion device showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the drug infusion device that form no part of the claimed design.

1 Claim, 4 Drawing Sheets
